UNITED STATES PATENT OFFICE.

ADNAH McMURTRIE, OF NEW YORK, N. Y., ASSIGNOR TO THOMAS & BETTS COMPANY,
OF NEW YORK, N. Y., A CORPORATION OF NEW YORK.

COILING-MACHINE.

1,117,684.

Specification of Letters Patent. Patented Nov. 17, 1914.

Application filed October 1, 1910. Serial No. 584,923.

To all whom it may concern:

Be it known that I, ADNAH McMURTRIE, of New York, N. Y., have invented certain Improvements in Coiling-Machines, of which 5 the following description, in connection with the accompanying drawings, is a specification, like references on the drawings designating like parts.

This invention relates to coiling machines, 10 and is of particular utility when employed in apparatus for manufacture of the helically coiled metal strip used as a protective armor sheath for insulated electrical conductors, although I contemplate the use of 15 my improvements in any field to which they are adapted by their nature.

An important object of my invention is to provide apparatus for, "setting" the somewhat resilient metal strip of which such 20 sheaths are usually formed, after it has been coiled helically by suitable shaping devices, so that the convolutions of the completed sheath will retain without substantial change the identical helical relation imparted to 25 the sheath by the coiling apparatus.

The method will be made the subject of a divisional application.

Another important object of my invention is to provide apparatus adapted to manufacture 30 such a sheath either as a tube constituting a separate entity to receive any suitable contents, or in combination with such articles as these or an insulated conductor or conductors introduced to the bore of the sheath 35 concurrently with its formation, as in the "flexible armored conductor" or "cable" well known to those skilled in the art.

When a plurality of insulated conductors are covered by a single sheath, frequently 40 they are twisted together so that their periphery does not present a cylindrical contour, and as a sheath of a cylindrical contour is for most purposes the best and most economical form to manufacture, an important 45 object of my invention is to provide means capable of forming a sheath having a bore closely approximating in diameter the twisted insulator conductor to be contained therein, without relying upon the conductors 50 to perform any function in shaping the sheath, and preferably obviating the use of any interior mandrel or adventitious shaping device other than the exterior rolls which constitute the preferred form of 55 means in my improved apparatus.

Among other objects of my invention is the provision of shaping devices of such a character that the same devices which arrange the strip in helical convolutions will impart to the strip the lateral offset along 60 the axis of the sheath necessary to convert a flat strip into a cylindrical helix, and I thus eliminate the expense and delay of the additional preliminary operation usually performed in a separate machine to impart a 65 lateral curvature to the heavy armor strip now required commercially, before it is introduced to the rolls which form the helix.

According to my improved method of coiling, I first shape helically the strip to be 70 coiled, and then set the helix, and this may be performed by any suitable means and at any suitable interval of time and space, but in the preferred form of apparatus which I have devised for the above purpose, I have 75 organized in a single machine a plurality of rolls constructed and arranged for engagement with the strip in a helical path, and operating in compact relation, so that the strip is offset, shaped and set in helical convolutions within a space of a few inches 80 along the axis of the completed sheath.

I may, furthermore, perform conveniently in this machine the operation of reducing a helical sheath of relatively larger diameter 85 to a smaller diameter. For this purpose I contemplate the use of tapered setting means. I may also utilize said machine for the application of the sheath to an insulated conductor concurrently with the formation of 90 the sheath, or to a hosepipe or similar article to be armored.

The various features of my invention will be illustrated and described fully in the accompanying drawings and specification 95 and pointed out in the claims.

In the drawings, Figure 1 is a view in front elevation of a machine for manufacturing flexible metallic armored cable in accordance with my invention, and in the construction of which my improvements have been embodied; Fig. 2 is a conventional sectional view on a larger scale, taken on the line x^2-x^2 Fig. 1, looking from right to left, parts being shown in elevation; Figs. 3 and 4 are sectional views in detail of modified forms of setting-roll; Fig. 5 is a sectional view of the form of strip to be coiled; and Figs. 6 and 7 are respectively views similar to Fig. 2 of modified forms of apparatus; 110

while Fig. 8 shows in elevation, and Fig. 9 in vertical section, a setting die of modified form.

In the embodiment of my invention selected for illustration and description as a convenient form of apparatus to permit a ready and complete understanding of the manner in which my improvements may be carried into effect, the part designated by 10 the reference numeral 1 is a shaping device, shown as a roll in the instance illustrated, to which is led a strip 5 of suitable material to be coiled into a helical sheath 10, the roll having a peripheral forming-surface 6 suitable 15 to be engaged with the curved outer surface 7 of the strip, and by such engagement to take part in the helical deformation of the strip.

To cooperate with roll 1 in effecting this 20 deformation, I may provide other forming devices of any suitable number and contour, arranged in any suitable relation, and in the instance illustrated I have shown in all four rolls, 1, 2, 3 and 4 whose peripheral forming surfaces 6 are so located along their respective axes that when led past each of these ridges for one complete turn the strip 5 will be formed into one complete helical convolution, being deformed laterally along its 25 axis sufficiently to acquire the helical lay of desired pitch. I prefer to drive these rolls, 1, 2, 3 and 4 positively, so that the helical sheath being formed will be given a forward rotative movement which clears it 30 from the rolls as it is formed, the edge 8 of the strip being interlocked with the edge 9 of the succeeding convolution, in well-known arrangement, and the coiled strip being advanced thus for the setting operation, 35 which constitutes another step in the effectuation of my invention, and may be accomplished by any suitable means.

As one convenient form of means to drive the rolls 1, 2, 3 and 4 positively, I have 40 shown them as provided respectively with arbors 31, upon which the rolls are secured by keys 32, these arbors being shown as journaled in suitable supports 40 and 41 secured removably, as by bolts 42, upon a 45 base 43, these parts being of any desired construction and arrangement suitable to support the arbors 31 rotatably. The actuation of the arbors 31 may in turn be accomplished by any suitable means, and I 50 have shown for this purpose gears 33, one for, and keyed at 34 to, each of the arbors, these gears intermeshing respectively with a central pinion 50 keyed at 51 upon a central shaft 60 which preferably extends 55 through central bearings 61 in the standards 41 and 40 to a region where it may be connected actuatively with a suitable source of power, the shaft being shown as provided, for this purpose, with a pinion 63 secured to 60 the shaft 60 by a key 64 and to be engaged

with a similar gear (not shown) driven by a suitable source of power.

The shaft 60 may be hollow if desired, its bore 65 serving at times to convey to the interior of the helical sheath such an article as the twisted, insulated conductor 70 which it may be desired to armor, and this conductor will preferably rotate with the hollow shaft 60 and helical sheath 10, within which sheath said conductor may fit with 75 any degree of closeness, a frictional contact being preferred in order to facilitate concurrent feeding of the conductor and sheath.

Reverting now to the means for accomplishing the setting operation, I have shown 80 as one form of such means a setting device 80 comprising a roll or set of rolls constructed and arranged to be engaged with, and roll about, the periphery of the helical sheath 10, having for that purpose a suitable 85 contour shown as taking the form of a helical thread 82 corresponding properly in pitch with the convolutions of the sheath 10 and so located as to engage firmly with the periphery of the sheath 10 and set the strip 90 in its proper helical form. If desired, these rolls may be tapered as shown in the modified form of roll illustrated at 83 in Fig. 3, to increase the setting pressure, and if found desirable the contour may be varied otherwise to meet the exigencies of particular installations, as for example, by adoption of the tapered smooth form 84 illustrated in Fig. 4.

Any suitable actuating means for the setting device may be employed, and as one such form of actuating device I have shown a rotatable setting head 90, recessed as at 91 to receive in protected position the rolls 80 mounted on screw studs 92, the head having a neck 93 journaled at 94 in an upright 95 of the base, a collar 96 with concealed set-screw 97 serving as one convenient form of means to hold the head in place. This setting head may be rotated by suitable actuating mechanism (not shown) for which purpose the pinion 98 is shown as a suitable gearing, and the setting head may have a suitable bore 99 for discharge of the shaped and set armor sheath 10.

In the modified form of apparatus illustrated in Fig. 6, the base 143, standards 140, 141 secured thereto by bolts 142, the forming rolls 101, 102, with forming-surfaces 106 and keyed at 132 respectively to arbors 131 120 provided with gears 133 keyed thereto at 134 and actuated by a pinion 150 keyed at 151 to a hollow driving shaft 160, the latter having a driving gear 163 keyed thereto at 164, for actuation from a suitable source 125 of power (not shown); these parts all may, and preferably will, be, substantially similar in construction and function with similar parts already described with reference to Fig. 2. I have provided this modified form 130

of machine, however, with a mandrel 166 by extending the hollow shaft 160 forward to a region between the setting devices, so that the strip 105 is first shaped helically at 5 a relatively large diameter and thereafter, during the setting operation the helical sheath is worked down, over the tapered forepart 155, of the mandrel, by the setting rolls 180 which are provided with a helical 10 peripheral forming surface 182 preferably, and are shown as carried by arbors 192 journaled in a setting head 190 mounted to rotate within a housing stand 195, provided with means, such as a screw stud 197 entering a groove 196 in the setting head to retain the latter in place. When actuated, as by the pinion 198, through suitable gearing (not shown) the setting rolls 180 act upon the helical sheath 110, tending constantly 15 to pull it along its axis down from the tapered forepart 155 of the mandrel with which the sheath is rotating, and the sheath will eventually be reduced as shown at the 20 left hand side of Fig. 6, will be set in final form and then discharged through the aperture 199 of the setting head. If desired, an 25 insulated conductor 170 may be thus covered, in the manner described with reference to Fig. 1, being introduced to the hollow 30 shaft at 165.

Passing to the modification illustrated in Fig. 7, the setting head 290 therein shown is provided with several sets of setting rolls each comprising a series of disk-like members 280 having preferably helical surfaces 282 corresponding in pitch with the convolutions of the helical sheath 210 upon which they act just as do the tapered helical rolls 180 of the machine shown in Fig. 6, these 35 setting disks being keyed at 392 to arbors 292 journaled in the setting head. I may, and prefer to, provide these arbors with pinions 393 meshing with a circular rack 394 fastened by pins 395 to the stand 295 so that 40 when the setting head is rotated by means of its outer pinion 298 the setting disks 280 will be caused to rotate positively, drawing the helical sheath 210 down from the taper 255 of the mandrel 266 and out through the 45 discharge aperture 299, these parts corresponding in function and operation with similar parts already described. So, also, no detailed description is needed for a proper 50 understanding of the structure and mode of 55 operation of the hollow mandrel shaft 260 rotating in standards 240 and 241, bolted at 242 to the base 243, the shaft serving, when actuated by its gear 263 to rotate the shaping rolls 201, 202, through their arbors 231 60 and gears 233 meshing with the gear 250 keyed to the shaft 260, inasmuch as the treatment of the armor strip 205 by the forming-roll-surfaces 206 proceeds in essential respects similarly to the mode of operation hereinbefore described. An insu-

lated conductor, as that shown at 270, may be thus armored, in the manner already described herein, and which will be understood readily by those skilled in the art.

In Figs. 8 and 9 I have shown a modified 70 form of setting device comprising setting-surfaces 382 formed upon setting members supported in any suitable manner for application to the periphery of the convolutions of a helical tube, and portions of these surfaces 382 may be inclined relatively to the axis of the helix as shown in their full-line position, for the purpose of reducing the diameter of the helix to a substantial extent 75 after its helical deformation, while a portion 80 of the setting-surfaces may, as illustrated at the left hand of Fig. 9, be substantially parallel with the axis of the helix. The relative proportions of these inclined and straight portions may be varied as desired 85 and found suitable, and the setting-surfaces may be substantially straight or inclined throughout, if required.

As one convenient form of support for these setting members 380 I have shown 90 them as integral with a setting head 390 adapted to take the place of the setting head 290 in the machine illustrated in Fig. 7, having a gear 398 like the gear 298, by which the head may be rotated, and a 95 groove 396 to receive the retaining screw 297. This setting head may be provided with a hub as indicated by dotted lines 393, to enter the bearing-standard 95 of the machine shown in Fig. 2. The setting head 100 may be split longitudinally and bolted together, and the setting-surfaces 382 can take the form of an interrupted screw, as illustrated, to reduce friction, or they may be substantially continuous.

Having illustrated and described my invention thus fully, and suitable means for carrying the same into effect, I wish it understood that I do not limit myself to the specific construction and materials 110 shown and described by way of example, nor in general do I limit myself otherwise than as set forth in the claims read in connection with this specification.

I do not claim specifically herein certain 115 features which are made the subject matter of claims in my co-pending applications Serial Nos. 584,924; 584,925; 584,926; 584,927, filed on the same date as my present application.

What I claim as new, and desire to secure by United States Letters Patent, is:—

1. A coiling machine; comprising means to deform a strip helically; and a rotatable setter head having a series of planetary rolls 125 revoluble upon axis parallel with the axis of said helix in peripheral engagement with said helix to compact the convolutions thereof.

2. Coiling apparatus; comprising a base; 130

14
a plurality of rolls having arbors journaled in bearing carried by said base, said rolls being constructed and arranged to deform a strip helically; a hollow shaft through which articles may be introduced between said rolls; means to drive said shaft, and means connecting said shaft actuatively with said arbors; and a setting head also journaled in bearings carried by said base and having planetary setting rolls to act peripherally upon said helix, said head having also means by which it may be driven.

3. A coiling machine; comprising a base; a plurality of standards supported thereby; arbors, a hollow driving shaft and a setting head journaled respectively in said standards; gears connecting said shaft actuatively with said arbors; rolls rotatable by said arbors to deform a strip helically; and a series of setting rolls mounted revolvably on said setting head and presented thereby in position adjacent to said deforming rolls for planetary engagement with the periphery of said helix, to set the convolutions thereof.

4. Coiling apparatus; comprising a mandrel; means coöperating therewith to coil a strip helically; a setting head; and a

series of setting-rolls mounted rotatably upon said head and revoluble thereupon in a planetary orbit, in peripheral engagement with said helix, said setting rolls being tapered and provided with forming surfaces to reduce said helix in diameter. 30 35

5. A machine for armoring electrical conductors; comprising a hollow rotatable shaft constituting a mandrel, and having a tapered forepart; a series of rolls coöperating with said shaft to deform a strip helically; and a setting head rotatable adjacent to the tapered portion of said mandrel and setting rolls revoluble with said head about the axis of said shaft, said rolls being constructed and arranged to reduce the diameter of said helix upon the tapered portion of said mandrel to approximately the diameter of a conductor fed therethrough, and said setting rolls having a portion to set the convolutions of said helix at said reduced diameter. 40 45 50

Signed at New York in the county and State of New York this 22nd day of September, 1910.

ADNAH McMURTRIE.
